UNITED STATES PATENT OFFICE.

SANFORD L. CLUETT, OF TROY, NEW YORK, ASSIGNOR TO CLUETT, PEABODY & CO., INC., OF TROY, NEW YORK, A CORPORATION OF NEW YORK.

COLLAR, &c.

1,397,921.

Specification of Letters Patent.

Patented Nov. 22, 1921.

Application filed October 29, 1919. Serial No. 334,358.

To all whom it may concern:

Be it known that I, SANFORD L. CLUETT, a citizen of the United States, residing at Troy, in the county of Rensselaer and State 5 of New York, have invented new and useful Improvements in Collars, &c., of which the following is a specification.

Reference may be had to the accompanying drawing, and the reference characters 10 marked thereon, which form a part of this specification. Similar characters refer to similar parts in the several figures therein.

This invention relates to collars and other buttonholed articles; the principal object of 15 the invention being to reinforce and strengthen the collar or other article at the end of the buttonhole which is subjected to pulling strain in use.

Other objects will appear in connection 20 with the following description.

The common expedient of inserting transverse bar-stitches at the end of a buttonhole, while having some utility, is greatly lacking in efficiency and causes the buttonhole 25 when it finally gives way to rip and tear at right angles to the length of the buttonhole along the line of the bar-stitches, and after reaching the end of the bar-stitches the rip or tear generally continues 30 in the direction of the line of pull.

In carrying out my invention, I employ bar-stitches extending divergently on opposite sides of the buttonhole at the end subjected to pulling strain, said stitches preferably being interlocked at their apex whereby 35 said bar-stitches act in the manner of a truss to transmit the pulling strain upon the end of the buttonhole to the threads of the fabric on opposite sides of the buttonhole at a substantial distance from said end; and the tendency of the fabric to tear 40 transversely at the end of the buttonhole is overcome.

The single figure of the drawing shows 45 on an enlarged scale a broken-away portion of a collar provided with a buttonhole made in accordance with my invention.

Referring to the drawing wherein the invention is shown in preferred form, 1 is 50 the broken-away end of a collar provided with a buttonhole, 2, formed by cutting through the plies of the collar.

This buttonhole is bordered on opposite sides by the usual buttonhole stitching 3.

Adjacent to the end of the buttonhole 55 which is subjected to the pull of the collar button in use, bar-stitches, 4, are inserted in the article extending divergently on opposite sides of the buttonhole.

These bar-stitches are preferably made to 60 overlap each other and interlock at their apex as shown.

Bar-stitches applied in this manner serve not only to directly resist pulling strain in directions substantially perpendicular to the 65 bar-stitches, but they act much in the manner of a truss to distribute direct pulling strain applied at the end of the buttonhole along the line of the buttonhole, to the threads of the fabric on opposite sides of the buttonhole at a substantial distance from its end.

I have ascertained by practical demonstration that a buttonhole made in this manner is able to resist a much greater pulling 75 strain, and more repeated pulling strains, than an ordinary bar and buttonhole, or than a buttonhole having a bar at its end extending horizontally or obliquely over one side only of the buttonhole. 80

I have shown the divergent bar-stitches at one end only, the other end of the buttonhole which is not subjected to pulling strain having the ordinary transverse bar-stitches, 5. 85

It will be understood however, that the divergent bar-stitches can be applied to either end or both ends of the buttonhole as may be found desirable.

What I claim as new and desire to secure 90 by Letters Patent is—

1. A buttonholed article having adjacent to an end of the buttonhole, bar-stitches extending divergently on opposite sides of the buttonhole, said bar-stitches being interlocked 95 with each other at their apex.

2. A buttonholed article having the usual buttonhole-stitches bordering the buttonhole-opening, and having at one end of the buttonhole bar-stitches extending divergently on opposite sides of the buttonhole, said bar-stitches being interlocked with each other at their apex. 100

In testimony whereof, I have hereunto set my hand this tenth day of October, 1919. 105

SANFORD L. CLUETT.
